PRODUCE TRAY

Raoul P. Lemieux, Fairfield, Maine, assignor to
Keyes Fibre Company, Portland, Maine, a corporation of Maine

Application September 22, 1952, Serial No. 21,542

Term of patent 14 years

(Cl. D58—13)

To all whom it may concern:

Be it known that I, Raoul P. Lemieux, a citizen of the United States of America, residing at Fairfield, county of Somerset, State of Maine, have invented a new, original, and ornamental Design for Produce Tray, of which the following is a specification, reference being had to the accompanying drawing, forming part thereof.

Fig. 1 is a top plan view of a produce tray, showing my new design;

Fig. 2 is a cross-sectional view thereof taken on the line 2—2 of Fig. 1; and

Fig. 3 is a cross-sectional view thereof taken on the line 3—3 of Fig. 1.

I claim:

The ornamental design for a produce tray, as shown.
